OMNIRANGE BEACON ANTENNA HAVING ROTATING PARASITIC CONDUCTIVE ELEMENTS

Sidney B. Pickles, Monterey, Calif., and James S. Engel, Tenafly, N.J., assignors to International Telephone and Telegraph Corporation, Nutley, N.J., a corporation of Maryland

Filed Jan. 5, 1955, Ser. No. 479,882

8 Claims. (Cl. 343—761)

This invention relates to omnirange beacon antennas and more particularly to directive antenna systems for producing a multiple modulation radiation pattern having a fundamental modulation frequency and one or more additional harmonics of the fundamental modulation frequency for use with omnidirectional beacons.

Omnidirectional beacon systems are known having a very high directional accuracy which are dependent upon the use of a rotating antenna pattern of a generally cardioid shape rotated at a fundamental frequency and modulated by a harmonic of this fundamental frequency so as to produce a generally multilobed rotating directive antenna radiation pattern. Due to the rotation of the special antenna pattern, a receiver located remotely from the transmitter receives energy which appears as an amplitude modulated wave having a fundamental modulation component and a modulation component at a harmonic frequency of said fundamental. Both fundamental and harmonic frequency reference signals are also transmitted omnidirectionally for comparison with the received components of the rotating pattern so that the receiver may determine its azimuth relative to the beacon's antenna system.

Previous antennas designed for use with such omnidirectional beacons have necessitated the use of rotating radio-frequency (R.-F.) joints or have been difficult to enclose for weather protection. Other known antenna systems have disclosed the production of the modulation frequency by the rotation of a parasitic element about a vertical stack of central radiators such as cones.

One of the objects of this invention therefore is to provide an improved omnidirectional beacon antenna system especially suited for use in the radiation of a rotating multilobed directive radiation pattern.

Another object of this invention is to provide an antenna system for producing a multilobed azimuthal directive pattern which may be completely enclosed so as not to be affected by weather elements.

A further object of this invention is to produce an antenna system for radiating a multilobed rotating directive radiation pattern without the use of rotating R.-F. joints.

In accordance with one of the features of this invention, a single rotating metal disk is used to form a support structure for parasitic modulation elements and to also provide counterpoise action for said elements. A vertical stub antenna radiates energy which is modulated by the rotating parasitic elements disposed at least at two different distances from said radiator to provide a directive multilobed radiation pattern for use in an omnidirectional beacon system.

The above-mentioned and other features and objects of this invention will become more apparent by reference to the following description taken in conjunction with the accompanying drawings, in which:

Fig. 1 is a view in perspective of one embodiment of the omnidirectional beacon system of this invention; and

Fig. 2 is a sectional view of the embodiment of the

2

antenna system taken along the lines 2—2 of Fig. 1 illustrating the arrangement of the center radiator unit and the feed system.

Referring to Figs. 1 and 2 of the drawing, an antenna system for producing a rotating multilobed shaped azimuth directivity pattern comprises a central radiator 1 supported at the center of a rotating disk 2. A harmonic frequency series of parasitic elements 3 spaced at regular angular intervals are affixed to the surface of an outer 10 rotating fiberglass housing 4 while a fundamental frequency group of parasitic elements 5 is attached to an inner fiberglass housing 6.

Referring more specifically to Fig. 2 of the drawing, a source of radio-frequency (R.-F.) energy is coupled 15 to a coaxial transmission line 10 having an inner conductor 10a and an outer conductor 10b. The inner conductor 10a is coupled to a central radiator 1 which essentially comprises a quarter wavelength vertical stub antenna. The outer conductor 10b has its direction reversed 20 to form a skirt 13 spaced from the central radiator 1 as shown by the distance "d." A rotating metal disk 2 functioning as a counterpoise surrounds the central radiator assembly. A quarter wavelength choke generally indicated at 14 is provided so that there is no leakage of 25 energy as the metal disk 2 rotates. Surrounding the central radiator assembly 1 is an inner fiberglass housing 6. The fundamental frequency parasitic group of elements 5 is carried by the inner fiberglass housing 6 which rotates about the central radiator 1. The elements 5 are insulated 30 from the counterpoise 2 by insulation 12. Also rotating with the metal disk counterpoise 2 is an outer fiberglass housing 4 on which a plurality of parasitic element groups 3 are carried for the harmonic modulation. The metal disk 2 providing a planar surface functioning as a counterpoise is rotated by means of a motor 21. The rotating metal disk 2 is separated by a quarter wavelength choke generally indicated at 14 from an extension of the counterpoise assembly 17 which surrounds the rotating portion of 35 the antenna system. The choke joint 11 at the center of the disk 2 is incorporated in order to prevent complications such as rotating R.-F. joints in the feed line 10 of the central radiator 1, thus allowing the central radiator 1 to remain stationary while the disk assembly 2 is rotating. It is apparent that parasitic elements can be placed 40 on the rotating disk 2 in any way necessary to produce the desired modulation frequencies. As shown in Fig. 1, the parasitic elements 5 carried by the inner fiberglass housing 6 produce a fundamental modulation having a frequency equal to the frequency of the disk's rotation. It 45 is apparent that each individual parasitic element in the group comprises a portion of conductive material above and perpendicular to the rotating disk and a portion parallel to the rotating disk. It is also to be noticed that the parasitic elements 5 are insulated from the counterpoise 2. The arrangement of the harmonic parasitic elements 5 provides means for tuning each element for a maximum 50 current by varying the length of element above and below the counterpoise 2 and also provides a means for lowering the center of radiation of the unit so that the radiation 55 may be directed with increasing amplitude at increasing vertical angles.

The harmonic modulation parasitic elements 3 are placed at properly chosen distances in accordance with the Bessel function expansion and are shown in Fig. 1 as 60 being carried by the outer fiberglass housing 4 coupled to rotating disk 2 in order to provide the harmonic modulation of the fundamental frequency. The counterpoise 2 is extended beyond the outer fiberglass housing 4 in order that the radiation pattern will have a marked differential 65 in radiated energy between vertical angles above the horizon and those below the horizon. The extension 17 of the counterpoise 2 is supported by means of weather-

proof housing 20. The greater the extension of the counterpoise 2 beyond the harmonic parasitic elements 3, the greater the differential in the signal directed above the horizon to that directed below the horizon. It is, of course, understood that it is highly desirable in an omnirange beacon antenna to have a large differential between the vertical angles above and below the horizon in order to allow the beacon to be sight free. The choke joint 14 is provided between the rotating portion of the counterpoise 2 and the extended skirt portion 17 in order to prevent a system having a large diameter from rotating. However, it is, of course, apparent that the outer choke joint 14 is not mandatory for purposes of this invention since an extension of the counterpoise beyond the harmonic parasitic elements 3 is not only practical, but will provide an appreciable up-tilt to the radiation pattern.

While we have described above the principles of our invention in connection with specific apparatus, it is to be clearly understood that this description is made only by way of example and not as a limitation to the scope of our invention as set forth in the objects thereof and in the accompanying claims.

We claim:

1. An antenna system comprising a conductive member having a planar surface, a radiator vertically disposed centrally of said surface and a plurality of parasitic conductive elements disposed in an electrically insulated relationship with said member for rotation about said radiator.

2. An antenna system comprising conductive means presenting a counterpoise surface, a radiator vertically disposed centrally of said surface, a plurality of parasitic conductive elements electrically insulated from and carried by said means with at least parts thereof above said surface, and means to rotate said means to cause said elements to rotate about said radiator.

3. An antenna system comprising a conductive member having a part suitable as a counterpoise surface, a radiator vertically disposed centrally of said surface, at least one dielectric cylinder carried by said member concentrically of said radiator, a plurality of parasitic conductive elements carried by said cylinder and means to rotate said cylinder about said radiator.

4. An antenna system comprising a conductive member having a planar surface, a radiator vertically disposed centrally of said surface, a plurality of dielectric cylinders carried by said member concentrically of said radiator, a first group of parasitic conductive elements carried by one of said cylinders and a second group of parasitic conductive elements carried by another of said cylinders and means to rotate said cylinders about said radiator.

5. An antenna system comprising a conductive member having a planar surface, a radiator vertically disposed centrally of said surface, a first group of parasitic conductive elements electrically insulated from and carried by said member disposed at a first distance from said radiator, a second group of parasitic conductive elements concentric to said first group electrically insulated from and carried by said member and disposed at a second distance from said radiator and means to rotate said members.

6. An antenna system comprising a conductive member having a planar surface having an inner area, a middle area and an outer area, the adjacent rims of each of said areas being flanged to form radio-frequency chokes, a radiator vertically disposed centrally of said surface, a first group of parasitic conductive elements carried by said middle area disposed about said radiator and a second group of parasitic conductive elements concentric to said first group carried by said middle area and means to rotate said middle area.

7. An antenna system comprising a conductive member having a planar surface, a radiator vertically disposed centrally of said surface, a plurality of dielectric cylinders carried by said member disposed concentrically about said radiator, a first group of parasitic conductive elements carried by one of said cylinders and disposed vertically to said surface and a second group of parasitic conductive elements carried by another of said cylinders disposed vertically to said surface and means to rotate said cylinders about said radiator.

8. An antenna system comprising a conductive member having an upper annular surface, a radiator vertically disposed coaxially of said annular surface, a first and second dielectric cylinder each carried by said member and disposed concentrically about said radiator, a first parasitic element assembly including a single group of conductors carried by the first of said cylinders and a second series of elements comprising a plurality of groups of conductors carried by the second of said cylinders and means to rotate said member and cylinders about said radiator.
